WILLIAM A. MCKAY AND MARTIN CLAUSSEN, OF SAN FRANCISCO, CALIFORNIA.

PORTABLE INCANDESCENT LAMP.

1,133,733.

Specification of Letters Patent. Patented Mar. 30, 1915.

Application filed February 6, 1913, Serial No. 746,505. Renewed February 8, 1915. Serial No. 6,821.

To all whom it may concern:

Be it known that we, WILLIAM A. MCKAY and MARTIN CLAUSSEN, respectively a Canadian subject of the King of Great Britain and a citizen of the United States, residing at San Francisco, in the county of San Francisco and State of California, have invented new and useful Improvements in Portable Incandescent Lamps, of which the following is a specification.

Our invention relates to improvements in portable incandescent lamps, and the object of our invention is to provide a lamp of this character, of simple and cheap construction, with means for securing it in various positions, as to the edge of a table or on a mirror, window pane, or other object having a comparatively smooth surface, or for suspending it from a hook or the like, and also with convenient means for winding up the loose lamp cord.

In the accompanying drawing, Figure 1 is a central vertical section of our improved lamp; Fig. 2 is a broken plan view thereof; Fig. 3 is a bottom plan view.

Referring to the drawing, 1 indicates the hollow body of a lamp stand formed out of sheet metal, and having a raised or concave bottom 2, in which are formed inwardly extending teeth 3, by which is secured within, and at the lower edge of, said hollow bottom, a ring 4 of rubber or the like, by which the lamp stand is supported upon a table or other horizontal surface. Said bottom is formed with a somewhat large central hole which is closed from below by a circular plate or disk 6, formed with two diametrically opposite flanged holes 7, the flanges 10 extending upwardly and being threaded. Into said threaded flanges 10 are screwed two tubes 8 externally threaded at their lower ends, their upper ends being externally flanged as shown at 12, and passing through holes, vertically above the holes 7 and formed in a circular cover plate 9, which plate 9 rests upon the top of the body 1, and has a circular flange 11 fitting around said top. The flanges 12 rest upon the upper surface of said cover, so that by screwing the lower ends of the tubes into said threaded flanges 10, the plate 6 is drawn upward, clamping between said plate and cover a winding cylinder 13. The cylinder is of such a length relatively to the height of that part of the body 1 between said plate and cover that thereby said body is held with

but little play in an axial direction and can turn freely therebetween. Upon one side of said cover are erected parallel standards 14, to the top of which are pivotally secured, by a bolt 15 and a nut 16, the side members 17 of a yoke 18, the middle portion of which is apertured and surrounds the neck 19 of an incandescent lamp socket 20. By means of said pivot said socket can be turned through any angle in a plane parallel with those of the standards. The cords 21 proceeding from said lamp socket are first wound around a tube 22 on said bolt 15 between said standards 14 and are then passed through a hole 23 in the cover 9 between said standards and into said hollow body 1 outside of the winding cylinder 13 contained therein. Said cords after passing around said cylinder any number of times desired then pass through a hole 24 in the body 1 to a connection plug 25. The central portion of said plate 6 is concaved upwardly and is formed with a central hole 27 through which passes a stem 28. The lower end of said stem, below said hole 27, is secured, as shown at 29, to the center of a suction cup 31 of rubber. A coiled spring 32, compressed between a washer 33 at its lower end and a shoulder 34 at its upper end formed by an enlarged portion 35 of the stem, normally presses said stem upwardly. The washer 33 is supported by a wire 36 around the stem, the further purpose of which will herein-after appear, which is itself supported by the plate 6, and the enlarged portion 35 of the stem with a snug fit passes through a central hole in the cover 9, so that said hole forms a guide for said stem. Upon pressure being applied by a finger to the upper end of the enlarged portion 35 of the stem, the suction cup 31 is projected beyond the lower edge of the rubber ring 4 at the bottom of the body 1. If it is so projected while said ring is in contact with a mirror, window pane, wall or other object having a comparatively smooth surface, the suction cup is more or less flattened against said surface, and, upon removing said pressure, the resiliency of the cup and of the rubber ring 4 and the pressure of the spring 32 restore the cup to its original form and a powerful vacuum is produced, holding the suction cup firmly to such smooth surface.

Through the tubes 8 pass the two terminal portions 41 of a wire clamp 43, on the ends of which terminal portions are secured

heads 43. Coiled springs 44 surround said terminal portions 41, and are compressed between said heads 43 and inwardly extending flanges 25 on the lower ends of the tubes 8, 5 thus tending always to press said clamp inwardly. The central portion of the wire clamp 46 is bent into a plane substantially at right angles to the terminal portions, and normally is received within the cavity in the 10 bottom of the hollow body. But when pressure by the fingers is applied to the heads 43, so that the terminal portions 41 are depressed against the action of said springs 44, then said central portion is projected to a 15 considerable distance below the rim of said hollow body, so that an object of considerable thickness, as the edge of a table or of a shelf or a bedpost, can be clamped between said clamp 46 and said rim.

20 The terminal portions of the wire 36 are extended to form guides for the sides 48 of a wire yoke 50, which sides pass through holes 49 in the plate 6, the center of said yoke then forming a loop for hanging the lamp upon a hook, nail or the like. Normally this yoke is contained wholly within the cavity of the 25 bottom of the hollow body, but its engagement with said holes and terminal portions is such that if a finger be applied to said loop portion of the yoke, it may be drawn through the holes 49, and extended beyond the edge of the bottom of the body. The ends of the yoke 50 are hooked, as shown at 30 51, to engage said terminal portions which thus arrest the outward movement of the yoke.

35 We thus provide a lamp stand, which, in a very small compass, contains several various contrivances for supporting it.

40 It will be observed that after the suction cup has been applied to a smooth surface, as a mirror, the cover, and, if desired, also the body, can be turned around said suction cup and stem through any angle, so that the electric lamp, and the reflector placed thereon, if desired, can be adjusted in position as required.

45 A valuable use of which our improved electric lamp is capable results from the fact that in such a lamp, for the first time, so far as we are aware, there has been provided an extensible cord and a clamp for clamping by spring pressure an object to the bottom of the lamp. For by this means the cord itself 50 can be clamped between the spring clamp and the body of the lamp, and the lamp can thus be used as a drop light, at any desired height.

55 We claim:—

60 1. In an electric lamp support, the combination of a hollow body, a cover closing the top of said body, means for revolvably securing together the cover and body, upwardly extending means on said cover for supporting a lamp, the cover and the side of the

body having holes to permit lamp cords to pass therethrough, and a winding spool within the body and secured to the cover, around which said cords are wound.

2. In an electric lamp support, the combination of a hollow body, having a centrally apertured top and bottom, a cover and plate closing the respective apertures, tubes connecting the cover and plate, a clamp having portions slideable in said tubes, and resilient 70 means for pressing said clamp to said body.

3. In an electric lamp support, the combination of a hollow body, having a centrally apertured and upwardly arched or concave bottom, a cover closing the top of said body, 80 a plate closing said aperture, tubes connecting the cover and plate, a clamp having terminal portions slideable in said tubes, its mediate portion being contained in said concavity, and resilient means for pressing said 85 clamp to said bottom.

4. In an electric lamp support, the combination of a hollow body, having a centrally apertured bottom, a plate closing said aperture, tubes connected with said plate, a wire 90 clamp having its terminal portions passing through said tubes and extending above the body, heads on the ends of said terminal portions, and coiled springs around said terminal portions between said heads and plate. 95

5. In an electric lamp support, the combination of a hollow body, having a centrally apertured top and bottom, a cover closing the top of said body, a plate closing said 100 aperture, tubes for connecting the cover and plate, a wire clamp having its terminal portions passing through said tubes and extending above the cover, heads on the ends of said terminal portions, and coiled springs around said terminal portions between said 105 heads and plate.

6. In apparatus of the class described, an annular casing, a cover-plate, a bottom plate, rotatably mounted on the respective sides of said casing, a spool interposed between said plates affording an annular chamber thereabout and within the casing, means for rigidly securing said plates and spool to rotate together, a lamp-socket mounted on said cover-plate, and a flexible 110 conducting-cord connected with said socket and extending within said chamber. 115

7. In apparatus of the class described, an annular casing, a cover plate, a bottom plate, rotatably mounted on the respective sides of said casing, a spool interposed between said plates affording an annular chamber thereabout and within the casing, tubular bolts connecting said plates and spool to rotate together, a lamp-socket mounted on 120 said cover-plate, and a flexible conducting-cord connected with said socket and extending within said chamber.

8. In apparatus of the class described, an annular casing, a cover-plate, a bottom 125

plate, rotatably mounted on the respective sides of said casing, a spool interposed between said plates affording an annular chamber thereabout and within the casing, 5 tubular bolts connecting said plates and spool to rotate together, and a spring-pressed clamp adapted to open upon the lower side of said casing having portions extending through said tubular bolts and 10 extending above said cover-plate.

9. In apparatus of the class described, an annular casing, a cover-plate, a bottom plate, rotatably mounted on the respective sides of said casing, a spool interposed between 15 said plates affording an annular chamber thereabout and within the casing, tubular bolts connecting said plates and spool to rotate together, and a spring-pressed vacuum sucker device seated in the 20 bottom of said casing having a stem extending axially through said plates.

10. In apparatus of the class described, a hollow casing provided with a circular bearing in its upper and lower surfaces and a recess in its bottom portion, a cover-plate 25 mounted on the upper of said bearings, a bottom plate engaging the lower of said bearings, tubular bolts adapted to secure said plates to rotate together, and a spool 30 interposed between said plates to rotate therewith.

11. In apparatus of the class described, a hollow casing provided with a circular bearing in its upper and lower surfaces, a cover-plate 35 mounted on the upper of said bearings provided with spaced standards on its outer face, a bottom plate engaging the lower of said bearings, means to secure said plates to rotate together, a spool interposed between 40 said plates to rotate therewith, a lamp-socket tiltably mounted on said standards, an electric conducting-cord connected with said socket and extending within said casing and thence outwardly through an aperture 45 in the casing whereby the rotation of said plates and spool will cause said cord to coil about the spool.

12. In apparatus of the class described, a hollow casing provided with a circular bearing 50 in its upper and lower surfaces and a recess in its bottom portion, a cover-plate mounted on the upper of said bearings, a bottom plate engaging the lower of said bearings, tubular bolts adapted to secure 55 said plates to rotate together, a spool interposed between said plates to rotate therewith, and a spring pressed clamp received within said recess and having actuating portions extending through said tubular bolts.

13. In apparatus of the class described, a 60 hollow casing provided with a circular bearing in its upper and lower surfaces and a recess in its bottom portion, a cover-plate mounted on the upper of said bearings, a bottom-plate engaging the lower of said 65 bearings, tubular bolts adapted to secure said plates to rotate together, a spool interposed between said plates to rotate therewith, and a spring-pressed clamp received within 70 said recess and having actuating portions extending through said tubular bolts and terminating in finger-engaging ends above said cover-plate.

14. In apparatus of the class described, a hollow casing provided with a circular bearing 75 in its upper and lower surfaces, and a recess in its bottom portion, a cover-plate mounted on the upper of said bearings, a bottom plate engaging the lower of said 80 bearings, tubular bolts adapted to secure said plates to rotate together, a spool interposed between said plates to rotate therewith, and a vacuum sucker received within 85 said bottom recess and provided with a stem extending through said plates and terminating in a pressable button protruding above said cover-plate.

15. The combination with a centrally apertured base having a stem to support a lamp or the like, of a suction cup, a stem to 90 which the suction cup is connected, slidably supported in the base and extending through the central aperture thereof, a spring tensioned to draw said cup within 95 the base, said suction cup being adapted to be projected out from the base against the tension of the spring.

16. The combination with a centrally apertured base having a stem to support a lamp or the like, of a suction cup, a stem to 100 which the suction cup is connected, slidably supported in the base and extending through the central aperture thereof, and a spring coiled about, and co-operating with, the stem 105 of the suction cup and normally maintaining said cup within the base, and a finger piece connected to the stem of the suction cup and extending through said aperture to project the suction cup from the base against the tension of the spring.

In testimony whereof we have hereunto set our hands in the presence of two subscribing witnesses.
